MORKRUM-KLEINSCHMIDT CORPORATION, OF CHICAGO, ILLINOIS, A CORPORATION
OF DELAWARE.

ELECTRIC SELECTING APPARATUS.

Original application filed December 23, 1919, Serial No. 346,948. Patent No. 1,635,486. Divided and this application filed November 4, 1926. Serial No. 146,211.

The present application is a division of the prior application filed by us in the United States Patent Office December 23, 1919, Serial No. 346,948 Patent No. 1,635,486.

5 The improvement relates to selecting apparatus for telegraphs and more particularly for printing telegraphs which employ a definite interval or unit code made up of permutations of two different line conditions 10 extending through a definite number of successive time intervals or units. The receiver selector mechanism for such telegraphs usually comprises a set of selectors corresponding in number to the selecting intervals 15 or units of the signal, and which are conditioned or set in different combinations in accordance with the code permutations. The present invention seeks to provide a simple selecting apparatus in which the 20 selectors are conditioned or set in different combinations under the joint mechanical control of a rotary, motor driven shaft, or its equivalent, and the armature of a single magnet which is responsive to the code permutations either of positive and negative or 25 of current and no current units. To this end the improved apparatus comprises a selector setting or conditioning member which is moved by a motor driven shaft or its equivalent and, preferably, in a circular path 30 through a series of positions corresponding in number to the selectors, together with a cam which cooperates with the motor driven shaft and is provided with a series of projecting cam lugs for shifting the selector 35 setting member at an angle to its path of movement to thereby effect the selector conditioning or setting operations, such operations being mechanically controlled by the 40 armature of a single selecting magnet. The invention further consists in the features of improvement hereinafter set forth, illustrated in the preferred form in the accompanying drawing, and more particularly 45 pointed out in the appended claims.

In the drawing:

Fig. 1 is a view in elevation of the selecting apparatus, parts of the supporting frame being shown in section. 50 Fig. 2 is a front elevation, and Fig. 3 is a rear elevation of parts shown in Fig. 1.

The improved selecting apparatus is under the joint mechanical control of a rotary, 55

motor driven shaft 10 and an electro-magnet 11 that responds to the received signals. The 55 shaft 10 is journaled in suitable plates or brackets 12 (only one of which is shown). It is continuously rotated during each complete selecting operation, preferably by means of a motor-driven, start and stop 60 clutch mechanism, such as set forth, for example, in the parent application, and which is initiated in operation in response to the starting interval or unit preceding the selecting intervals of each signal, and is arrested 65 in response to spacing intervals between the signals.

The magnet 11 is mounted on the bracket 12 and its armature 13 on a vertical, spring-held lever 14 that is pivotally mounted at its 70 lower end. In the form shown, the armature lever is provided with an annular part or cam-ring 15 which surrounds and is concentric with the shaft 10 and is provided with a series of internal cam lugs 16. These 75 cam lugs are preferably five in number and they correspond to the selecting intervals of the signals.

A sleeve 17, fixed to the shaft, has a lug 18 thereon to which an actuating arm 19 is 80 centrally pivoted. This arm is provided with inclined cam ends which co-operate respectively with the inclined faces of the cam lugs 16 and with the forward ends of a series of selector members 20. The latter are 85 mounted upon the bracket 12 in a circular series concentric with the shaft 10 and are preferably in the form of longitudinally movable pins mounted in bushings 21 that extend through openings in the plate or 90 bracket 12. Preferably, as set forth in the parent application, the pins serve to shift or position a set of selectors in the form of longitudinally movable plungers 22 which in turn control all the printing operations. 95 The rear ends of these plungers extend through a plate 23 fixed to the upper end of the bracket 12 and engage the upper ends of a series of levers 24. The latter are pivotally mounted between their ends on studs 25 fixed 100 to and projecting rearwardly from the plate 12, and the lower ends of the levers are engaged by the rear headed ends of the pins 20. For the sake of clearness, only one plunger, lever and pin are shown in Fig. 1, 105 but as indicated in Figs. 2 and 3, there are

five of these parts corresponding to the selecting intervals of the signals.

A spring 26 connected to the sleeve 17 and the arm 19 tends to hold the rear end of the 5 arm against a stop lug 27 on the sleeve. As the actuating arm is rotated by the shaft, the armature lever is shifted by the magnet to vibrate the cam ring and move the lugs 16 thereon into and out of the path of movement of the forward end of the actuating arm, and the rear end of the arm is shifted by the cam lugs into and out of operative relation with the selector pins 20. The cam lugs 16 are spaced in accordance with the 10 spacing of the pins, the beveled edge of each lug being arranged slightly in advance of the corresponding pin.

The shaft 10 is continuously advanced in the direction indicated by the arrow in Fig. 20 during each complete selecting operation, and the spacing of the cam lugs and pins and the timing of the shaft are such that the actuating arm is brought into line with the inclined portions of the cam lugs during the 25 mid-portions of the selecting intervals of the signals. During such interval, the circuit is the magnet 11 is either closed or opened to thereby shift the cam in axial direction either to its operative or inoperative 30 position, so that as the arm moves past each of the selecting pins 20, the latter either remains in its normal forward position or is shifted rearwardly to thereby advance the corresponding selector plunger 22. In this 35 way the selectors are set in different combinations during each complete operation. Suitable means are provided, such as shown in the parent application, for restoring the selector plungers and pins to normal at the 40 end of each operation.

The angular spacing of the cam lugs and pins is, as stated, such that the selector setting operations occur during the mid-portions of the selecting intervals of the signals. This spacing of the lugs and pins is 45 uniform, except that the space between the end lugs and pins of the two series is considerably greater to allow for the movement of the actuating member during the starting 50 and spacing intervals or units of the signal.

Obviously, the controlling magnet 11 can be arranged to respond either to positive and negative impulses, or to current and no current intervals. Other changes may be made 55 in the details set forth without departure from the scope of the invention as defined in the appended claims.

We claim as our invention:

1. An electric selector mechanism for telegraph receivers comprising a set of selectors, a common actuator for mechanically positioning said selectors, a rotary member for mechanically moving said actuator into relation with said selectors one at a 60 time, a cam having a series of angularly 65

spaced projecting lugs for mechanically shifting said actuator at an angle to its path of movement to position said selectors, and a magnet having an armature mechanically and selectively controlling the selector positioning operations of said cam. 70

2. An electric selector mechanism for telegraph receivers comprising a set of selectors, a common actuator for mechanically positioning said selectors, a rotary member 75 for mechanically moving said actuator into relation with said selectors one at a time, a cam having a series of angularly spaced projecting lugs for mechanically shifting said actuator transversely of the path of movement to position said selectors, and a magnet responsive to received signals for shifting said cam into and out of operative 80 position.

3. A selector for telegraph receivers responsive to definite interval code signals having starting, selecting and spacing intervals and comprising a set of selectors, a common actuator adapted to be continuously advanced into relation with said selectors in succession during each signal period, a cam having a circular series of projecting lugs angularly spaced as described in accordance with the starting, selecting and spacing intervals of the signals, for 85 shifting said actuator transversely of its path of movement to position said selectors, and a magnet having an armature mechanically controlling the selector positioning operations of said cam. 90

4. A selector for telegraph receivers responsive to definite interval code signals and comprising a set of selecting elements arranged in a circular series, a common rotary actuator adapted to be continuously advanced into relation with said selectors in succession, a cam having a circular series of projecting lugs for shifting said actuator transversely of its path of movement to position said selecting elements, said selecting 105 elements being uniformly spaced except for the relatively greater spacing of the end elements of the series and said cam lugs being correspondingly spaced, and a magnet responsive to received signals and having 110 an armature mechanically controlling the selector-positioning operations of said cam. 115

5. A selector mechanism for electric telegraphs comprising a circular series of selecting elements, a rotatable and radially movable actuator for positioning said selecting elements in different combinations, a motor-driven shaft for effecting the rotary movement of said actuator, a magnet responsive to received signals and a member vibrated by said magnet for selectively controlling the radial movement of said actuator. 120
